UNITED STATES PATENT OFFICE

SOL WEICHSEL, OF LOS ANGELES, CALIFORNIA

DESIGN FOR A PANEL FOR LIGHTING FIXTURES

Application filed May 28, 1929. Serial No. 31,432. Term of patent 3½ years.

To all whom it may concern:

Be it known that I, Sol WEICHSEL, a citizen of the United States, residing at Los Angeles, in the county of Los Angeles and State of California, have invented a new, original, and ornamental Design for Panel for Lighting Fixtures, of which the following is a specification, reference being had to the accompanying drawing, forming a part thereof.

In the accompanying drawing Fig. 1 is a front elevation of the device showing my new design; Fig. 2 is a side view thereof.

I claim:

The ornamental design for a panel for lighting fixtures substantially as shown.

SOL WEICHSEL.
